UNITED STATES PATENT OFFICE.

CONRAD VENTER, OF DENVER, COLORADO.

WAVE MOTOR.

Application filed May 1, 1925. Serial No. 27,250.

My invention relates to improvements in wave motors, and it consists in the combinations, constructions and arrangements herein described and claimed.

5 An object of the invention is the provision of a simple, reliable and efficient device which affords facilities for making use of the power that resides in incoming waves to drive a shaft for operating an air 10 compressor or like mechanism.

A further object of the invention is the provision of a wave motor of the character described which will be positive in action and is not likely to get out of order easily.

15 Other objects and advantages of the invention will be apparent from the following description, considered in conjunction with the accompanying drawing, in which—

Figure 1 is a side elevation of my improved wave motor.

Figure 2 is a section substantially on the line 2—2 of Figure 1, and

Figure 3 is a section substantially along the line 3—3 of Figure 1.

25 In carrying out the invention, I make use of a substantially vertical obstruction 1 against which incoming waves 2 impinge. The obstruction 1 may be the face of a cliff or of an embankment or other suitable structure. The supporting structure of the device includes a pair of spaced standards or columns 3 which are fixed to extend above the level of the waves in front of the obstruction 1. The horizontal supporting shaft or

35 rod 4 extends between the upper end portions of the standards 3 and is supported by the latter to be substantially parallel to the plane of the obstruction 1. The standards 3 are stayed to the obstruction 1 by horizontal stay bars 5 having the inner end portions thereof secured to the top of the obstruction 1 and the outer end portions thereof secured to the upper ends of the standards 3.

40 The motion transmitting mechanism of the motor comprising a pair of vertically swingable arms 6 which are pivotally supported adjacent to their outer ends on the shaft 4 as best seen in Figure 3 and are stayed to each other at their outer ends by a cross bar 7. The arms 6 carry an impact plate 8 which has the lateral edge portions thereof secured on the arms 6 by rivets 9 or like fastening devices. The plate 8 extends from the inner ends of the arms 6 to a level above the level of the waves 2 and both the inner end portion of the

plate 8 and the inner end portions of the arms 6 are curved downwardly substantially along the arc of a circle as indicated at 10 in Figure 1. The arms 6 and the plate 8 together form a pivoted lift member which is swingable vertically in response to the force resulting from the impact of the incoming waves against the under face of the inner end portion of the lift member, the lift member being pivotally supported at its outer end and being inclined downwardly and inwardly toward its inner end so that the inner end of the lift member will depend into the water adjacent to the obstruction 1. The arms 6 preferably are right angular in cross sectional contour as clearly shown in Figs. 2 and 3.

45 A horizontal shaft 11 extends between the arms 6 adjacent to the inner ends of these arms and is supported by the arms 6. A rack bar 12 is pivotally supported adjacent to its lower end on the shaft 11 and extends through an aperture 13 in the plate 8 above the level of the obstruction 1. A pair of diagonal brace bars 14 are pivotally supported at their lower ends, as at 15 on the shaft 11 and extend through the aperture 13, being fixedly secured at their upper ends to opposite sides of the rack bar 12, whereby the rack bar will be held against movement axially of the shaft 11 and is permitted to rock about the axis of the shaft 11 and to move in a vertical plane with the inner end of the lift member. The vertical face 50 of the rack bar 12 nearest to the obstruction 1 is slightly convex in curvature and is provided with a series of teeth 16 which are upwardly inclined and are adapted to mesh with inclined teeth 17 of a pinion 18 to rotate the pinion 18 in a clockwise direction when the rack bar 12 moves upward and to slide over the teeth of the pinion 18 on the downward movement of the rack bar. The pinion 18 is secured on a horizontal shaft 19 which is mounted in aligned bearings 20 at the upper ends of vertical supports 21 on the obstruction 1. A fly wheel 22 is secured on the shaft 19 and may depend in a recess or cavity 23 in the top of the obstruction. A bevel ring gear 23 may be rigid with the fly wheel 22 in concentric relation to the shaft 19 and in mesh with a smaller bevel gear 24 which is secured to a shaft 25. The latter is supported in a bearing 26 at the upper end of a support 27 on the obstruction and may transmit motion to an air com-

pressor, such as that shown diagrammatically at 28 in Figure 1 or may be used to transmit motion to any other suitable mechanism that is to be driven.

From the foregoing description of the various parts of the device, the operation thereof may be readily understood. The impact of the incoming waves on the lift member will cause the latter to swing from the full line position in Figure 1 to the dotted line position in Figure 1 or toward the dotted line position in Figure 1, thereby causing upward movement of the rack bar 12 and imparting a torque to the shaft 19 through the pinion 18. The invention contemplates that there shall be very little friction, if any, between the rack bar and the pinion during the downward stroke of the rack bar and that the fly wheel 22 shall function in conjunction with the pinion 18 to cause continuous rotation of the shaft 19 in one direction, the fly wheel functioning to cause rotation of the shaft 19 during the down stroke of the rack bar. If desired, suitable known mechanism, such as a clutch between the pinion 18 and the shaft 19 may be employed to positively disconnect the rack bar from the shaft 19 during the downward stroke of the rack bar.

Obviously, the invention is susceptible of embodiment in forms other than that which is illustrated in the accompanying drawing, and I therefore consider as my own all such modifications and adaptations thereof as fairly fall within the scope of the appended claims.

I claim:—

1. A wave motor comprising a supporting structure upstanding above the water in front of an obstruction at the edge of a body

of water, a lift member comprising a pair of spaced arms pivotally supported at their outer ends on said supporting structure and depending inwardly and downwardly toward said obstruction, the inner ends of said arms being free to swing in an arc about the axial line of the pivotal supports of the outer ends of said arms, a lift plate secured on the inner end portions of said arms, a pinion rotatably supported on said obstruction, a rack bar pivotally attached at its lower ends to said lift member and having teeth for engaging with the teeth of the pinion during the upward stroke of the rack bar and for disengaging the teeth of the pinion during the downward stroke of the rack bar, the inner end portion of said plate and said supporting arms of the lift member being curved downwardly.

2. A wave motor comprising a supporting structure upstanding above the water in front of an obstruction at the edge of a body of water, a lift member comprising a pair of spaced arms pivotally supported at their outer ends on said supporting structure and depending inwardly and downwardly toward said obstruction, a lift plate secured on the inner end portions of said arms, a pinion rotatably supported on said obstruction, a rack bar pivotally attached at its lower ends to said lift member and having teeth for engaging with the teeth of the pinion during the upward stroke of the rack bar and for disengaging the teeth of the pinion during the downward stroke of the rack bar, the face of said rack bar nearest to said obstruction and on which said teeth are provided being slightly convex in curvature from its upper end to its lower end.

CONRAD VENTER.
